CLAIM

The ornamental design for a touch panel control interface, as shown and described.

DESCRIPTION

FIG. 1 is a front perspective view of the touch panel control interface in accordance with the present invention;
 FIG. 2 is a rear perspective view thereof;
 FIG. 3 is a front elevation view thereof;
 FIG. 4 is a rear elevation view thereof;
 FIG. 5 is a top plan view thereof;
 FIG. 6 is a bottom plan view thereof;
 FIG. 7 is a left side elevation view thereof; and,
 FIG. 8 is a right side elevation view thereof.
